CATHODE FOR ELECTROLYTIC CELLS

Allen C. Jephson and Ernest B. Custer, Johnstown, Pa., assignors to National Radiator Corporation, a corporation of Maryland

Application July 25, 1934, Serial No. 736,897

1 Claim. (Cl. 204—6)

This invention relates to electrolytic cells, and more particularly to cells used for the deposit of metal in sheet form upon a rotating cathode, and consists in features of structure by virtue of which the cell is best adapted to service conditions and is of superior utility.

In the accompanying drawings Fig. I is a view in plan from above of the cell of the invention; Fig. II is a view of the cell in vertical and axial section; Fig. III is a view in plan and to larger scale of the rotating cathode structure alone; Fig. IV is a view in side elevation of the cathode structure, with details shown in axial section; Figs. V and VI are fragmentary views in elevation, illustrating details.

The cell 1, conveniently formed of concrete, and borne (with rubber insulation between) upon suitable posts 2, is of annular shape, and is arranged with its axis in vertical alignment its outer wall 3 and its inner wall 4 rising from the bottom wall 5. The inner wall becomes indeed a post of concrete with axial bore 6, rising from the bottom wall 5 of the cell.

The anode 7 is here shown to be a split annulus of 1-inch steel plate of such breadth as to extend throughout a substantial part of the depth of the cell, and, when the parts are assembled, throughout the breadth of the reception surface of the cathode. The annulus is of such size as to surround at a narrow interval (an inch and a half, in this instance) the reception face of the assembled cathode. The annular anode 7 rests upon steps 8 formed in the bottom of the cell.

Current flow to the anode is effected through bars 9 secured electrically to the anode upon its outer surface and extending over the outer rim of the cell. These bars (here shown to be eleven in number—the number is of no inherent significance) are spaced at substantially equal intervals around the circumference of the anode. The bars 9 at their outer ends are electrically united by bands, 10, 11, of hard-drawn copper, through which the current for electrolysis is distributed to the bars, and through the bars to the anode.

Within the cell and exteriorly of the anode heating means are arranged. The heating means shown consist of a coil 12 of pipe, for carrying steam or other heating fluid.

The cathode structure includes a shaft 13, adapted in the assembly (as shown in Fig. II) to extend vertically within the bore 6 of the central post 4 of the cell, arms 14 extending radially from the shaft, a cylindrical shell 15

carried by the arms, and a reception band 16 carried by the shell. The band 16 is endless and practically inextensible; the shell is split and is expansible and contractible, and it is by virtue of the contraction and expansion of the shell that the band may be applied to and then mechanically secured in electrical union upon it.

The shaft, conveniently formed of cold rolled steel, bears pinned to it at its upper end a hub 17 of cast copper. The hub is formed with a downward-facing shoulder 18, and this shoulder, meeting an opposed shoulder formed upon a casting 19 that caps the post 4, sustains the cathode structure in position. An antifriction device (ball bearing) 20 interposed between casting 19 and hub 17 relieves the soft metal of wear and facilitates rotation.

It is from the hub 17 that the arms 14, also formed of copper, immediately extend; and with the hubs the arms are both mechanically and electrically united.

The shell 15 is advantageously made of aluminum plate; it is truly cylindrical; and its outer surface is finely finished and free of defects. It is, as has been said, a split shell, and it is rendered contractible and expansible by means of bolts 21 that extend through holes in aligned tongues 22, slit from the opposite edges of the plate and turned inward. By the turning of the nuts 23 upon the bolts the described adjustment of the shell is effected. The shell 15 is conveniently secured upon the outer ends of arms 14 by means of tongues 24 slit from the shell and turned inward, to which tongues 24 the arms 14 are mechanically and electrically united.

The shell is re-enforced by rings (also discontinuous) 25 of aluminum, tack-welded to the interior surface of the shell; and welded also to the tongues 22 and 24.

The hub 17 terminates upwardly in a spindle 26, adapted to be engaged in electrical union (while rotation of the spindle continues) by a pair of spring-backed contact blocks 27, through which the circuit that feeds the anode is completed.

In the upper end of spindle 26 is set an eye-bolt 28, by means of which the cathode structure, engaged by suitable apparatus, may be raised and lowered.

The reception band 16 that is mounted upon and carried by the shell 15 corresponds in vertical extent and in position with the anode, as clearly appears in Fig. II.

The shaft 13 is but a portion of a multiple- 55

piece shaft, whose other parts are in Fig. II indicated at 29 and 30. Shaft parts 13 and 29 are freely separable and unitable by vertical displacement, by means of the tongue-and-groove union illustrated in Figs. II, IV, and V. Shaft parts 29 and 30 are provided with flanges 31, and are united by the bolting together of these flanges, in an electrically insulated but mechanically rigid union. Bakelite gaskets are placed between the abutting horizontal surfaces of shaft parts, flanges, and nuts, and the shanks of the bolts are wrapped with insulating tape.

The shaft parts being assembled and united as described, it is manifest that rotation, imparted to the lowest shaft part 30 will be effective to rotate the cathode structure as a unit; and suitable means are provided for imparting rotation at proper speed immediately to the shaft part 30.

In consequence of forming the shaft of a plurality of parts, and of prolonging the shaft part 13 with which the hub 17 and the shell 15 are rigidly and inseparably connected to form a unit, so that it extends downward to and beyond the lower rim of shell 15 and in the assembly meets and makes union with the shaft part 29 deep in the bore 6 of the central post 4 of the cell, the shaft part 13 becomes a positioning member, and the bore 6 a guide, so that the

cathode structure in its introduction into and in its removal from the cell is controlled in position and guided. And by such provision the highly finished and carefully cleaned surface of the cathode band 16, and the newly deposited sheet as well, are restrained from accidental contact with or striking against other parts, and so is guarded and protected against mutilation and contamination.

We claim as our invention:

A rotatable cathode for an electrolytic cell including a hub of electrically conducting material provided with a cylindrical surface adapted to be engaged by contact blocks in an engagement permissive of rotation, conducting arms electrically united with and extending from said hub, an expandable and contractible cylindrical shell of conducting material electrically united with and borne by said arms, an endless band of conducting material adapted to be secured in electrical union upon said shell by the expansion thereof, and a shaft integral with said hub and extending concentrically within said shell and shaped at its free end to the form of one element of a rotation-imparting shaft-coupling.
